DESIGN FOR A DRESS

Julia Richards, Brooklyn, N. Y.

Application January 21, 1941, Serial No. 98,221

Term of patent 3½ years

To all whom it may concern:

Be it known that I, Julia Richards, a citizen of the United States, residing in Brooklyn, New York city, in the county of Kings and State of New York, have invented a new, original, and ornamental Design for a Dress, of which the following is a specification, reference being had to the accompanying drawing, forming part thereof.

Figure 1 is a front view of a dress, showing my new design; and

Figure 2 is a rear view of Figure 1.

The characteristic feature of my design resides in the combination on the fly-front dress disclosed of the specific contrasting wide ribbed double collar and narrow ribbed cuffs in association with the specific tucking above and below the waistline on each side of the fly-front opening, all as shown.

I claim:

The ornamental design for a dress, substantially as shown and described.

JULIA RICHARDS.
